[57] CLAIM

The ornamental design for a combined golf car and removable canopy therefor, as shown.

DESCRIPTION

FIG. 1 is a perspective view of a combined golf car and removable canopy therefor showing my new design;

FIG. 2 is an enlarged perspective view thereof with the canopy removed for convenience of illustration;

FIG. 3 is a side elevational view of FIG. 2;

FIG. 4 is a top plan view of FIG. 2;

FIG. 5 is a rear elevational view of FIG. 2;

FIG. 6 is a top plan view of the removable canopy with the golf car omitted for clarity of illustration;

FIG. 7 is a side elevational view of FIG. 6;

FIG. 8 is a bottom plan view of FIG. 6;

FIG. 9 is a front elevational view of FIG. 6; and

FIG. 10 is a rear elevational view of FIG. 6.
